UNITED STATES PATENT OFFICE

EDWARD J. SCHREMP, OF BEACHHURST, LONG ISLAND, NEW YORK, ASSIGNOR TO THE PROSPERITY COMPANY, INC., OF SYRACUSE, NEW YORK, A CORPORATION OF NEW YORK

HOSIERY-PRESSING TRAY

Application filed March 15, 1923, Serial No. 625,428. Renewed September 24, 1925.

This invention relates to pressing machines and equipment therefor; and more particularly it relates to improvements in hosiery pressing trays useful in connection with 5 pressing machines for finish pressing hosiery and other knit goods products.

An object of the present invention is to produce an improved hosiery carrying device in the form of a tray capable of receiving and 10 holding in proper shape a large number of hose, gloves, or other knitted apparel for the purpose of being simultaneously pressed and stamped with transfer tape to imprint the manufacturer's name, brand, or trade mark 15 thereon; and it is likewise an object to produce a hosiery pressing tray light in weight, inexpensive to manufacture, and which is readily useful in knit goods manufacturing plants for finishing hosiery and making them 20 ready to be packed.

With the above principal objects and others in view, the invention is illustrated in the accompanying drawings showing an embodiment thereof, serving to disclose the principle, the construction, and operation thereof; and the arrangement of parts and the use 25 thereof may be variously modified without departing from the scope of my invention as set forth in the appended claims.

30 Figure 1 shows a plan view of the hosiery pressing tray carrying a plurality of forms; and some of the forms have hose placed thereon ready for pressing.

35 Figure 2 illustrates a transverse cross-sectional view taken on the line 2—2 of Figure 1.

Figure 3 illustrates a longitudinal cross-sectional view taken on the line 3—3 of Figure 1.

40 Figure 4 shows a cross-sectional view taken on the line 4—4 of Figure 1; and Figure 5 illustrates a plan view of the structure shown in Figure 4. These last two mentioned figures serve to illustrate a snap lock device employed to hold the hosiery tray in open and 45 closed position so that it may be rapidly handled and shifted from place to place without the hosiery pressing forms becoming displaced.

50 Figure 6 is an end view of the form sup-

porting shaft showing two locking grooves which serve to hold the device in position.

Referring now more particularly to the drawings for a detailed description of the invention, there is shown a rectangular frame 55 10 preferably made of channel pressed steel to impart rigidity and strength with a minimum weight. The frame is fitted with a shaft or stringer member 11 which is journaled in bearings 9 anchored in the frame 10; 60 and this shaft is adapted to undergo a rocking motion, and remain fixed in either one of two positions at which the said lock shaft may be placed. The end of the shaft projects slightly from the edge of the frame, 65 15 and has formed therein two grooves 13 and 14 right angular one to the other.

A flat steel spring 15 is anchored to the frame and carries a lug 12 which is the counter-part of the grooves 13 and 14; and 70 the pressure of the flat spring 15 urges the lug or rib 12 into one or the other of the grooves 13 or 14, yet the pressure of the flat spring 15 is sufficiently yieldable as to permit the shaft 11 to be rotated, and for this purpose the lug 12 is rounded over so as to back out and away from the groove during the rotation of the shaft 11. It is to be observed that this construction affords a positive locking means for holding the shaft 11 75 in one of two positions. It is preferable to arrange this locking means at each end of the shaft in order that the position thereof be positively held against accidental rotation.

The shaft or rod 11 is made with a handle 16 preferably located at each end of the shaft and anchored thereto. The operators using this hosiery pressing tray grasp either one of the handles 16 for setting the correct position of the shaft 11, and subjects the said shaft to rotation, thereby overcoming the pressure of the springs 15; and when the shaft is moved to a certain position the snap catch engages the next groove in the shaft 80 thereby holding the shaft in proper position.

85 A plurality of hosiery forms 17 or in fact glove forms, or other knit goods forms, are anchored at one end thereof to the shaft 11 which causes the forms to reach across the frame 10. The said hosiery forms 17 are 100

spaced as closely as practical while at the same time they must not interfere with one another because sufficient room must be provided as will enable the operators to quickly place the hose S or other knit goods apparel, upon the said forms.

A spring clip 19 is anchored to each end of the frame 10 and serves as a spring snap fastener to hold transfer printing tape T in position. The ends of the said tape T are clipped under the fasteners 19 which tautly disposes the tape across the foot portions or toe portions of the hose S to be pressed. The transfer tape T carries the hosiery manufacturer's trade mark name B, or brand, or other indicia which it is desired to imprint upon the said hosiery.

In the operation and use of this hosiery pressing tray, the shaft 11 is given a quarter turn which brings the plurality of hose carriers or forms 17 into a vertical position. The hose S are then placed over the forms and by pressing the handle 16 downwardly, the said filled forms are moved into a horizontal position in alignment with the frame 10. The printed transfer tape T is now stretched across the tray in contact with the knitted goods S; and the tray is loaded and ready to be inserted in a pressing machine.

30 Any suitable form of pressing machine may be employed, for subjecting the knitted goods S to pressure. It is preferred however, to use steam heated pressing machines with polished metal faces, in order that the hot 35 faces thereof may impart a sheen to the knit goods during the pressing operation. The application of heat and pressure transfers the brand or mark B carried on the transfer tape T upon the knit goods S, thereby imprinting the hosiery with the manufacturer's trade mark or brand.

This pressing tray is preferably made slightly longer and wider than the pressing surfaces or head and bucks into which the 45 device is placed in order that the heated pressing faces of the pressing machine may be applied only to the knit goods S without coming into engagement with the frame or parts thereof other than the hose S and 50 forms 17.

This device fills a long felt want in knit goods factories, and will enable the manufacturers to speed up production because of the rapidity with which the hosiery may be 55 pressed and stamped and made ready for packing.

What I claim is:

1. A pressing device comprising a frame, a rotatable shaft journaled in the frame, 60 means for rotating the shaft, a lock to fasten the shaft in position, and forms on the shaft to carry work to be pressed.

2. A pressing device comprising a frame, a rotatable shaft therein journaled, means 65 for rotating the shaft, means to lock the shaft

in position, forms on the shaft to carry knit goods, and means for supporting printed transfer tape on the frame adjacent the forms.

3. A pressing device for holding hosiery and the like in pressing machines comprising 70 a frame, a plurality of apparel forms movably carried in the frame, means for moving said forms into vertical position and lowering the forms to a horizontal position.

4. A hosiery pressing device consisting of 75 a frame, a hosiery carrier embodying a plurality of forms, a shaft journaled in the frame and carrying the forms, a locking device co-operating with the shaft to lock the forms in desired position.

5. An apparel pressing form consisting of 80 a rigid frame, a plurality of forms carried within the frame, and fastener means by which transfer tape is held on the frame in 85 position to be pressed.

6. An apparel pressing form comprising 90 a frame, a shaft journaled therein, locking grooves made in the shaft ends, a snap lock engageable with the grooves, and a plurality of forms anchored to the shaft and swingable relatively to the frame for placing and removing apparel on and off the forms.

7. A pressing tray for holding hosiery and the like in pressing machines comprising a 95 frame, a plurality of apparel forms movably carried in the frame, means for moving said forms into vertical position and lowering the forms to a horizontal position, and means carried on the frame to hold transfer printing tape across the forms.

8. An apparel carrying device comprising 100 a rigid stringer member, and a plurality of apparel forms carried with the rigid member, and held parallel to each other to hold a plurality of pieces of work in parallel relation for treatment in a press or the like.

9. An apparel carrying device comprising 110 a rigid stringer member, a plurality of rigid apparel forms mounted on the rigid member in the same plane, and a handle fixed to the member by which the device is handled to place work in a press or the like.

10. An apparel carrying device comprising, a stringer member, a plurality of garment holding forms having one end attached thereto and disposed in the same plane, said forms being adapted to stand up for receiving garments and lie down to make ready for drying and pressing operations, and 115 means for holding a strip of transfer tape across the device in contact with the garments on the forms for printing the garment during the pressing operation.

11. A work holding and treating device 125 comprising a rod, a plurality of garment forms having one end thereof fixed to and projecting in the same direction from said rod adapting the device to be readily inserted and removed from a pressing machine by 130

which the manual handling of a plurality of pieces of work is facilitated.

12. A device for use in connection with simultaneously stretching and laying a plurality of garments in a pressing machine, comprising a shaft, a plurality of garment forms fixed in parallel relation and in the same plane to the shaft, and said device being adapted to manual operation in removing the work from a pressing machine for loading and unloading the garments from the forms.

15. In testimony whereof I affix my signature this 13th day of March, 1923, in the city of Rochester, county of Monroe, and State of New York.

EDWARD J. SCHREMP.
